(57) **CLAIM**

The ornamental design for a necklace, as shown and described.

DESCRIPTION

FIG. 1 is a front view of a necklace showing my new design; FIG. 2 is a rear elevational view thereof; FIG. 3 is a right side elevational view thereof; FIG. 4 is a left side elevational view thereof; FIG. 5 is a top plan view thereof; FIG. 6 is a bottom plan view thereof; FIG. 7 is an enlarged partial front view of the necklace shown separately for completeness of illustration; FIG. 8 is a rear elevational view thereof; FIG. 9 is a right side elevational view thereof; FIG. 10 is a left side elevational view thereof; FIG. 11 is a top plan view thereof; and, FIG. 12 is a bottom plan view thereof. The broken lines are for illustrating the environment and form no part of the claimed design.
